D. E. WILLARD.
DOOR HANGER SUPPORT.
APPLICATION FILED MAR. 12, 1911

1,120,777.

Patented Dec. 15, 1914.

UNITED STATES PATENT OFFICE.

DONALD E. WILLARD, OF DANVILLE, ILLINOIS, ASSIGNOR TO ALLITER-PROUTY COMPANY, OF DANVILLE, ILLINOIS, A CORPORATION OF ILLINOIS.

DOOR-HANGER SUPPORT.

1,120,777.

Specification of Letters Patent. Patented Dec. 15, 1914.

Application filed March 12, 1914. Serial No. 324,668.

To all whom it may concern:

Be it known that I, DONALD E. WILLARD, a citizen of the United States, residing at Danville, in the county of Vermilion and State of Illinois, have invented certain new and useful Improvements in Door-Hanger Supports, of which the following is a specification.

My invention relates to tracks for sliding door hangers. It is essential that such tracks shall be rigid so as to carry the weight without deflection and adapted to permit the wheels of the hangers to travel thereon without obstruction. Such tracks are usually made either from tubes (generally slotted) or from flat bars, and are supported by means of separately formed brackets either removably or rigidly connected with the tracks. In some instances it has been proposed to form the track and its support integrally from sheet metal. It is desirable to provide such tracks and track supports with a housing which shall protect the tracks from obstruction due to snow, sleet, etc., and to prevent the passage of snow, rain, sleet and dust over or its lodgment upon the upper edge of the door. Usually the water shield where one is used is formed separately from the door supports and track. My invention has for its purpose to provide these several necessary or desirable features in a structure which is of integral formation and such as may be readily stamped or pressed from sheet metal thus reducing the cost of manufacture and application.

My device can be made in any desired lengths but for economy of manufacture it has been found best to make it in standard lengths—say six or eight feet and to connect two of such sections together by a simple joint piece inserted in the adjoining ends of the track portions.

In the accompanying drawings Figure 1 is a cross-sectional view through the track, its supports and the shield, and Fig. 2 is an elevation of the outer side of the device.

In the drawings A represents the sheet from which the track, its supports and the shield are formed; B the hanger, C the track wheel, D the door, and E the joint piece.

The metal sheet or plate A is suitably pressed or stamped to provide the vertical attaching flange 10 perforated as at 11 for the passage of an attaching bolt or lag screw, the outwardly inclined roof portion

12, the vertical portion 13, the longitudinal curved track portion 14 and the shield or apron 15. The curvature of the track portion will be such as to conform to the groove of the wheel and since the track surface is convex and is shielded from the elements it will not be liable to obstruction. There is thus formed a housing for the hanger and the upper edge of the door which affords not only ample protection from the elements but also prevents the wheel of the hanger from displacement. By reason of the convex cross-sectional shape of the track and the concaved shape of the periphery of the wheel, the door may swing outward when struck by a vehicle or by reason of other causes. Furthermore, the substantially semi-tubular shape of the track together with the spacing of the shield from the lower edge of the body portion of the device permit upward yielding of the shield under the tilting or swinging of the door without danger of breaking any of the portions of the device.

The structure is sufficiently strong to support heavy doors and may be used with various forms of hangers.

When the track is put up in sections I may use a simple joint piece such as the split tube E telescoping the abutted ends of the hollow tracks of the connected sections.

There is provided by my invention a suspension flange, a housing over the top and outer side of the hanger, a track and a water shield or apron all formed integrally from a relatively thin metal plate. This construction is rendered possible by reason of the fact that the various parts are so disposed as to avoid sharp curves or angular bends while the disposition of the suspension flange, vertical side member, convex track section and shield are in parallel planes and the transverse width of the structure is such that the device is sufficiently rigid to prevent distortion under the load, while attaining extreme simplicity and economy in construction and ease in application.

I claim:

1. A means for supporting sliding doors constructed from a single sheet of metal and comprising a vertical attaching flange at its upper margin, an outwardly extending portion constituting a roof or housing for a wheel hanger, a vertical member constituting the body portion of the supporting means, an inwardly-extending reversely-

- curved portion affording a longitudinal trough-like depression adjacent to said body portion, and a convexly curved track portion of semi-cylindrical form, and an outwardly-extending terminal portion constituting a shield for the top of the door, said shield portion being spaced apart from the lower edge of the body portion, substantially as described.
- 10 2. The combination with a sliding door having a hanger rising therefrom and a grooved suspending wheel carried by the hanger, of a door support formed from a single sheet of metal and comprising a vertical attaching flange at its upper margin, an outwardly-extending portion constituting a roof or housing for a wheel hanger, a vertical member constituting the body
- 5 portion of the supporting means, an inwardly-extending reversely-curved portion 20 affording a longitudinal trough-like depression adjacent to said body portion, and a convexly-curved track portion of semi-cylindrical form, and an outwardly-extending terminal portion constituting a shield for 25 the top of the door, said shield portion being spaced apart from the lower edge of the body portion, and the door being free to tilt outwardly at its bottom upon the semi-tubular track as a fulcrum, substantially as 30 described.

DONALD E. WILLARD
